US0D1013870S

(12) **United States Design Patent** (10) **Patent No.:** **US D1,013,870 S**
(45) **Date of Patent:** **** Feb. 6, 2024**

(54) **MENSTRUAL CUP**

(71) Applicant: **Menstrual Mates, Inc.**, Lewes, DE (US)

(72) Inventors: **Cynthia Belardo**, West Lafayette, IN (US); **Drew Jarvis**, Bloomington, IN (US); **Benjamin Ettinger**, Evergreen, CO (US); **Sean Kleinschmidt**, Carmel, IN (US); **Grant Chapman**, Indianapolis, IN (US)

(73) Assignee: **MENSTRUAL MATES, INC.**, Ashland, MA (US)

(**) Term: **15 Years**

(21) Appl. No.: **29/864,365**

(22) Filed: **May 24, 2022**

(51) LOC (14) Cl. **24-01**

(52) U.S. Cl.

USPC **D24/141**

(58) **Field of Classification Search**

USPC **D24/141, 121, 124-125**
CPC **A61F 6/06; A61F 6/08; A61F 6/12; A61F 5/4553; A61F 5/455; A61F 13/2045**

Primary Examiner — Wan Laymon

(74) Attorney, Agent, or Firm — DINSMORE & SHOHL LLP

(57) **CLAIM**

The ornamental design for a menstrual cup, as shown and described.

DESCRIPTION

FIG. 1 is a first perspective view of a menstrual cup showing our new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom plan view thereof.

The broken lines shown in the drawings are included for the purpose of illustrating portions of the menstrual cup that form no part of the claimed design.

1 Claim, 7 Drawing Sheets
